(57) **CLAIM**

The ornamental design for a shoe cover, as shown and described.

DESCRIPTION

FIG. 1 is a left side view of a shoe cover, the right side view being a mirror image thereof;

FIG. 2 is a front view thereof;

FIG. 3 is a rear view thereof;

FIG. 4 is a top view thereof;

FIG. 5 is a bottom view thereof;

FIG. 6 is a left side view of the shoe cover of FIGS. 1–5 shown in use, positioned over an exemplary shoe for illustration;

FIG. 7 is a front view thereof;

FIG. 8 is a rear view thereof;

FIG. 9 is a top view thereof; and,

FIG. 10 is a bottom view thereof.

The broken lines shown on the heel and on the sole of the shoe cover are included for the purpose of illustrating portions of the shoe cover that form no part of the claimed design. Additionally, the broken lines shown in FIGS. 6–9 are included for the purpose of illustrating environmental structure that forms no part of the claimed design.

1 Claim, 8 Drawing Sheets
